DESIGN FOR A KNIFE

Leo F. Baker, Chicago, Ill., assignor of one-half to Agnes Scanlon Baker, Chicago, Ill.

Application December 13, 1944, Serial No. 116,873

Term of patent 7 years

(Cl. D22—3)

To all whom it may concern:

Be it known that I, Leo F. Baker, a citizen of the United States and resident of Chicago, in the county of Cook and State of Illinois, have invented a new, original, and ornamental Design for a Knife, of which the following is a specification, reference being had to the accompanying drawing, forming a part thereof.

Fig. 1 is a side elevational view of a knife, showing my new design.

Fig. 2 is an edge view thereof.

I claim:

The ornamental design for a knife, substantially as shown.

LEO F. BAKER.
